UNITED STATES PATENT OFFICE.

PETER J. COPPENS, OF GRAND RAPIDS, MICHIGAN.

STOVE.

SPECIFICATION forming part of Letters Patent No. 752,144, dated February 16, 1904.

Application filed June 3, 1903. Serial No. 159,896. (No model.)

To all whom it may concern:

Be it known that I, PETER J. COPPENS, a citizen of the United States, residing at Grand Rapids, in the county of Kent and State of Michigan, have invented certain new and useful Improvements in Stoves; and I do hereby declare the following to be a full, clear, and exact description of the invention, such as will enable others skilled in the art to which it applies to make and use the same.

My invention relates to improvements in stoves, and more particularly to stoves adapted to burn either hard or soft coal or wood; and its object is to provide the same with a fire-pot that may be easily constructed and repaired, to provide means for properly supplying the fuel with hot and cold air currents, to provide a device that will produce economic and smokeless combustion, to provide a secure fastening for attaching the sheet-metal body to the fire-pot and protecting the same from the action of the fire, whereby the stove is made more durable, and to provide the same with certain new and useful features herein-after more fully described, and particularly pointed out in the claims, reference being had to the accompanying drawings, in which—

Figure 1 is a plan view of a fire-pot of a stove embodying my device; Fig. 2, a vertical section of the same on the line 2 2 of Fig. 1; Fig. 3, a plan view of the fire-pot casting proper with the detachable parts removed; Fig. 4, an enlarged detail, in vertical section, on the line 4 4 of Fig. 2; Fig. 5, the same on the line 5 5 of Fig. 1, but omitting the member G; and Fig. 6, a detail in horizontal section on the line 6 6 of Fig. 2.

Like letters refer to like parts in all of the figures.

A represents the fire-pot casting proper, having its walls divided into a number of segmental portions spaced apart and the intervening portions recessed outward, as at B, to form heating-flues for the incoming air. The upper parts of the portions A are each extended outward to the radius of the portions B, and thence upward to form the outer portion C of the annular air-chamber at the top of the fire-pot. All of the parts B and C terminate at

the top in an integral outwardly-projecting flange E, to which the sheet-iron body is secured, as hereinafter described. The upper part of one of the portions B and a portion of the flange E adjacent thereto are removed, and an outwardly-extended intake D for cold air is provided, which intake is closed by a suitable door F, hinged at F' and forming a part of the ring M. The truncated conical wall of the fire-pot is completed by the insertion of detachable sections I, provided with vertical slots or openings J to admit the air to the fuel. These sections are extended upward and outward to form a part of the inner side of the before-mentioned air-chamber and are provided with a flange I' to attach to the inner surface of the sheet-metal body L. To complete the air-chamber of the fire-pot, segments G are inserted between the outwardly-curved portions of the sections I, with their lower edges resting on the angle at the junction of the parts A and C, and are provided with suitable openings H for the escape of the air from the aforesaid chamber and also provided with a flange G' to attach to the inner surface of the body, the flanges I' and G' forming segments of a continuous flange engaging the inner surface of the body L at the top of the air-chamber. Grooves K are provided at intervals in the upper part of the fire-pot A to permit the ashes to escape from the said air-chamber. The body L is flanged outward at the bottom and seated upon the flange E, and an outwardly and downwardly extended ring M is provided, having a bead N at the angle to engage and bind the angle of the body and an upwardly-projecting flange O opposite the flanges G' and I', and in these parts are inserted bolts P and P', as shown, whereby all the detachable parts are securely attached to the fire-pot, and the sheet-metal body is prevented from becoming detached, warped, or loosened by the action of the heat. The described device is also very easily repaired. By removing the bolts P the portions I or segments G, or any one of the same, may be removed and another inserted without disturbing any other part of the stove, and the en-

tire structure can be taken apart by removing all of the bolts P and P', which is very easily done.

In operation when the door F is closed a portion of the air admitted to the base passes up through the flues back of the sections I, becoming heated therein and escaping inward through the openings J and H. In the event that the fire-pot is only partially filled the air will escape through the openings J close above the fuel, and in the event that the fire-pot is filled to the top the air-chamber will distribute this heated air to the various openings H therein. By excluding the air from the base of the stove and opening the door F cold air is admitted to the air-chamber and passing inward over the fire tends to check the combustion. In the event that the fuel is low in the fire-pot the cold air will flow down the flues and escape through the opening J close above the fuel.

I thus provide a device that is simple in construction, easily repaired and operated, and producing very satisfactory combustion of the fuel when in use whether the fire-pot be full or only partially filled.

Having thus fully described my invention, what I claim, and desire to secure by Letters Patent, is—

- 30 1. In a stove, a fire-pot having an outwardly-projecting flange and an upwardly-projecting flange at the top, a sheet-metal body surrounding the upwardly-projecting flange and having an outwardly-projecting flange resting on the corresponding flange of the fire-pot, a ring surrounding the body and extending horizontally and vertically opposite the flanges on the fire-pot, and bolts extending through the ring, the flanges, and the body.
- 40 2. In a stove, a fire-pot having its walls composed of a number of segmental portions spaced apart and extended outward and upward at the top, the intervening portions being recessed outward to form air-heating flues, detachable sections interposed between the said segmental portions to complete the circuit of the fire-pot and extended upward and outward to form a portion of the inner side of the air-chamber, and segments interposed between the upper part of the detachable sections to complete the inner portion of the air-chamber.
- 50 3. In a stove, the combination of a fire-pot consisting of a truncated conical portion comprising a number of segments spaced apart and extended outward and upward at the top, the intervening portions being recessed outward and extended upward to the plane of the top of the segments, detachable portions between the segments to complete the circuit of the fire-pot and extended upward and outward, and also provided with vertical slots to admit air, segments between the upper parts of the detachable portions, and flanges on the upper edge of the detachable portions and the last-

named segments to attach the same to the 65 body of the stove.

4. In a stove, the combination of a fire-pot having a truncated conical portion, and an outwardly and upwardly extended portion forming the outer part of an air-chamber, a 70 flange surrounding the upper part of the said extended portion for attaching the sheet-metal body of the stove, segments forming the inner portion of the air-chamber and resting on the top of the truncated conical portion of the 75 fire-pot, a flange on the upper edge of the segments, and means for attaching the flange to the body of the stove.

5. The combination of a fire-pot having grooves to permit the escape of ashes from 80 the air-chamber, and an outward and upward extension forming the outer part of the air-chamber, a flange on the extension to attach the sheet-metal body, segments forming the inner part of the air-chamber and provided 85 with air-openings, flanges on the upper part of the segments, and means for attaching the flanges to the sheet-metal body.

6. The combination of a fire-pot having segmental portions spaced apart and extended 90 outward and upward at the top, the intervening portions being recessed outward to form flues, detachable portions between the said segments and provided with slots to admit air and also extended upward and outward to 95 portions of the inner side of the air-chamber and attached to the body at their upper ends, an outwardly-projecting flange surrounding the upper edge of the fire-pot, segments forming the remaining portions of the inner side 100 of the air-chamber and attached to the body, a cold-air inlet opening into the air-chamber, and a movable door to close the same.

7. In a stove, the combination of a fire-pot having an outwardly-projecting flange, a 105 sheet-metal body having an outwardly-turned flange resting on the flange of the fire-pot, an air-chamber in the upper part of the fire-pot and having a vertical flange engaging the inner surface of the sheet-metal body, a ring 110 surrounding the sheet-metal body and having a vertical flange opposite the flange on the air-chamber, bolts extending through said flanges, and bolts extending through the ring and through the flange on the fire-pot.

8. In a stove, the combination of a fire-pot having an outwardly-projecting flange, a stove-body having a flange resting on the flange of the fire-pot, an air-chamber in the fire-pot and having a vertical flange engaging the inner 120 surface of the stove-body, an outwardly-projecting ring above the flange on the fire-pot, and having a vertical flange engaging the outside of the body and opposite the flange on the air-chamber, an outwardly-projecting air-inlet to the air-chamber, and a door to open and close the inlet and forming a portion of the ring.

9. In a stove, the combination of a fire-pot, an outwardly-projecting flange at the top of the fire-pot, a vertical flange on the fire-pot, a sheet-metal body surrounding the vertical flange, a flange on the body engaging the horizontal flange, a ring surrounding the body and extending vertically and horizontally opposite the flanges on the fire-pot, a bead on the ring and engaging the angle of the body, and bolts extending through the ring, flanges and body.

10. In a stove, the combination of a fire-pot, an outwardly and upwardly extended portion to the same forming the outer side of the air-chamber, a horizontal flange at the top of the extended portion, a sheet-metal body having an outwardly-extended horizontal flange resting on the flange of the fire-pot, detachable

sections forming portions of the inner side of the air-chamber, and extending downward to 20 form portions of the fire-pot, detachable segments forming the remainder of the inner side of the air-chamber, vertical flanges on the said segments and detachable portions and engaging the inner surface of the sheet-metal body, 25 and a ring surrounding the body and extending vertically and horizontally, and opposite the flanges on the fire-pot, segments and sections, and fastenings extending through the ring, the flanges and the body.

In testimony whereof I affix my signature in presence of two witnesses.

PETER J. COPPENS.
